TOY

Edmund R. Gulden, Gladstone, Minn.

Application December 18, 1933, Serial No. 702,944

2 Claims. (Cl. 272—55)

The present invention relates to a child's toy, and more particularly to a combined riding and bobbing toy with adjustable means for accommodating children of different weights.

5 An object of the present invention is to make an improved and simplified child's toy.

In order to attain this object, there is provided, in accordance with one feature of the invention, a supporting frame having a spring arm thereon, the free end of said spring arm having a seat adjustably mounted thereon. A bobbing element is mounted in a well in front of the spring supported seat and is connected by an operating cord to the seat so that on operation 10 of the toy the bobbing element will ride up and down in the well in view of a child seated on the device.

These and other features of the invention will be more fully brought out in the following description and the accompanying drawing, wherein:

Figure 1 is a plan view of the device embodying the present invention.

Figure 2 is a side view of the device shown in Figure 1; and

Figure 3 is an end view of said device.

Referring to the drawing in detail, a longitudinal frame member 1, which may be of wood, has a transverse rear frame member 2 fixedly secured thereto, supporting knobs 3 and 4 being provided at the outer ends of said transverse frame member 2. A rectangular well 5 is fixedly secured transversely of the forward end of the longitudinal frame member 1 and knobs 6 and 7 are provided on the lower end of the well to support the device.

A bobbing element 8 is mounted for free, slideable movement in the well 5, and is here shown as comprising a representation of a clown.

40 An operating cord 9 passes over a pulley 10 mounted on the upper edge of the rear of the well, the cord 9 passing around a pulley 11 at the lower end of the rear wall of the well and around a pulley 12 mounted below the longitudinal frame member 1, the cord then passing freely through an opening 13 drilled in the frame member 1. The cord is connected to a fastening member 14 in a seat member 15.

This seat element is preferably saddle shaped, 50 as shown, and may have a representation such as the head of a horse 16 mounted on the forward end thereof, with a transverse hand grip member 17 mounted therein. The seat 15 is mounted on a leaf spring 18 being fixedly secured in position thereon by means of the bolts

19 and 20. A pair of loops 21 and 22 are secured in position by means of bolts 23 to bind the spring 18 to a second leaf spring 24 which is securely fastened by means of a strip 25 to the longitudinal base member 1, the lower end 26 of the 5 spring 24 fitting into a recess in the well 5 to secure the leaf spring 24 in position.

A transverse foot support 27 is carried by the lower loop 22 so that a child may rest its feet on this foot piece 27 while operating the mechanism. 10

In use a child seats itself on the seat 15, grasps the handle 17 and rests its feet on the foot piece 27, and, by moving its body up and down or back and forth, the seat 15 is caused to bob up and down against the resilient action of the springs 24 and 18. The cord 9 on a downward movement 15 of the seat 15 permits the weight of the bobbing element 8 to draw the cord 9 downwardly into the well, dropping the bobbing element 8 and 20 when the resilient action of the springs 24 and 18 return the seat 15 upwardly, the cord 9 is drawn with it to move the bobbing element 8 upwardly in the well.

To adjust the spring tension, if it is desired to 25 increase the resiliency of the seat action, the bolts 23 may be loosened to release the loops 21 and 22 and the spring 18 may then be slid outwardly away from the well 5 to increase the length of the spring action. As the child grows older, or 30 if it is to be used by a heavier child, the bolts 23 may be loosened to free the loops 21 and 22 and the spring 18 may then be slid inwardly toward the well 5 to stiffen the spring action. Thus full 35 adjustability of the mechanism is provided for the extreme difference in weights of which the device is capable.

The mechanism is simple and safe in operation, and the fact that the connection between the seat 15 and the bobbing element 8 is concealed from the child, lends an element of mechanical mystery in the mind of the child which greatly enhances its appeal, much more so than if a direct connection were to be made, for instance, on a spring supported, vertically slideable 45 bobbing element, as has been previously done in older constructions.

I claim:

1. In a device of the character described, a base element, a leaf spring fixedly secured thereto and having an end thereof projecting freely therefrom, a seat element having a leaf spring secured thereto and projecting outwardly therefrom, said seat spring element and said base spring element being secured together for ad- 55

justment longitudinally to vary the spring tension on said seat.

2. A device of the character described, comprising a spring supported seat, a bobbing element mounted forwardly of said seat to be visible by an operator riding on said seat, a cord

connected to said seat, pulleys mounted intermediate of said seat and said bobbing element, said cord passing around said pulleys and being connected to said bobbing element to operate said bobbing element on an actuation of said seat. 5
